ADVERTISING SIGN FOR DRIVE-IN RESTAURANTS OR THE LIKE

Frank P. Thomas, Zionsville, Ind., assignor to Burger
Chef Systems, Inc., Indianapolis, Ind., a corporation of Indiana

Filed Nov. 25, 1960, Ser. No. 62,973

Term of patent 14 years

(Cl. D1—12)

Fig. 1.

Fig. 2.

FIG. 1 is a front elevational view of an advertising sign for drive-in restaurants or the like embodying my new design, the rear being a mirror image thereof; and

FIG. 2 is a right side elevational view thereof, the left side being substantially the same in appearance.

I claim:

The ornamental design for an advertising sign for drive-in restaurants or the like, as shown and described.
